UNITED STATES PATENT OFFICE.

EDWARD S. SAVAGE, OF ROCHESTER, NEW YORK, ASSIGNOR TO THE TODD COMPANY, INC., OF ROCHESTER, NEW YORK, A CORPORATION OF NEW YORK.

PRINTING APPARATUS.

Application filed April 13, 1925. Serial No. 22,740.

This invention relates to printing apparatus and more particularly to the hand operated variety adapted for printing monetary values and other protective legends upon bank checks and similar negotiable instruments. The effectiveness of such protective legends depends largely upon the use of a sufficient quantity of ink to impregnate the paper and render the impression indelible and hence the efficiency of apparatus of this character requires full inking of the type before each impression is made. One object of the present invention therefore is to provide a machine of this character having an improved inking means of a simple, reliable and effective construction for insuring full inking of the type forms preliminary to each impression of the same upon the paper. A further object is to provide in combination with such means a simple and practical construction for feeding the work after each impression is made.

To these and other ends the invention resides in certain improvements and combinations of parts, all as will be hereinafter more fully described, the novel features being pointed out in the claims at the end of the specification.

In the drawings:—

Figure 1 is a top plan view of a machine embodying the present invention;

Figure 2 is a sectional view on the line 2—2^a in Figure 4;

Figure 3 is a similar view showing the parts, however, in the position which they occupy while making an impression;

Figure 4 is a sectional view on the line 4—4^a in Figure 2, and

Figure 5 is an enlarged perspective view of parts of the feeding mechanism detached.

Similar reference numerals throughout the several views indicate the same parts.

The invention is embodied in the present instance, by way of illustration, in a printing apparatus or checkwriting machine comprising a frame having a lower or base portion 10, Figures 1 and 2, on which is supported an upper casing portion 11. Between these portions is an inwardly extend-

ing work receiving slot 12 above a work bed 13 on the base on which the work is placed to receive the impression. The upper portion 11 of the casing carries in the present instance a rotary type wheel having on its periphery a plurality of type forms adapted to be brought by rotation of the wheel selectively to printing position above a platen in the base 10 which is raised to press the work against the type by operating means comprising a handle 14, the latter operating also a feeding mechanism for feeding the work between successive impressions.

The platen is preferably in the form of a metal block 15 having an upper impression surface 16 which, like the faces of the type, is preferably ridged or corrugated to scarify the paper as an incident to the impression of the same to promote absorption of and impregnation by the ink to render the impression indelible. The platen is secured in any suitable manner in a slot 17 in the forward end of a platen lever 18 pivotally supported intermediate its ends on a shaft 19, the ends of which latter are mounted in the sides of the base 10.

The operating means for effecting the relative impressing movement of the type wheel and platen comprises, in the present instance, a toggle mechanism formed by a pair of links 20 and 21 pivotally connected with each other as at 22, link 20 being pivotally connected with the rear end of the platen lever at 23. The toggle link 21 is fixed on a shaft 24 rocking in bearings in the sides of frame portion 11 and projecting through one side of the same for the attachment thereto of the operating handle 14. A spring 25 tends to maintain the handle raised and the platen lowered ready for the insertion of the work.

The printing wheel is shown at 26 as fixed on a shaft 27 rotating in bearings at its ends in the sides of frame portion 11 through which one end of the shaft projects and carries an operating knob 28. The periphery of the wheel is provided with a plurality of type forms 29 spaced circumferentially about the same for cooperation individually

and selectively with the platen. The type wheel carries at one end a dial 30 marked with characters representing the type forms, the dial being visible through a slot 31 in the frame encasing the same, so that by manually turning the knob 28 any desired character on the dial may be selected and brought to registry with an index 32 on the frame at the side of the dial. Such selection of the character for printing locates the same for contact with inking means during the impressing movement as hereafter described.

The inking means comprises preferably an inking roll 33 rotatably mounted on a spindle 34 carried by an arm 35 pivotally mounted on a spindle 36 on a bracket 37 fixed on a cover plate 38 on the frame. A spring 39 presses the ink roll toward the type wheel so that it lies in the path of rotation of the type forms at a point spaced as shown from the printing position over the platen. Cover plate 38 is pivotally supported on a spindle 40 and closes an opening in the top of the frame through which the ink roll is raised for reinking when the cover is swung back on its pivot.

Means are provided in conjunction with the ink roll for insuring contact therewith of each type form selected for printing as an incident to the impression of the same, whether it be impressed one or a number of times in succession. Such means comprises, preferably, a plurality of cam slots 41 formed in one end on the printing wheel, one slot corresponding to each of the type forms. Cooperating with these slots is a follower 42 in the form of a pin or roller carried on the forward end of a member or arm 43. The latter is arranged for movement upon each actuation of the operating means, being in the present instance formed integrally with the upper toggle link 21. These parts are so constructed and arranged that while the type wheel is left freely rotatable to select the type forms, such selection by means of the indicating device already described brings the selected type form into contact with or just above the inking roll 33. Subsequent operation of handle 14 to impress the same on the work causes arm 43 to swing downwardly, whereby its follower 42 engages the corresponding cam slot in the type wheel and swings the latter so that the selected type form is moved from contact with the inking roll direct into printing position above the platen, before the latter rises above the printing bed. Upon release of handle 14 after the impression, the parts return to the position shown in Figure 2 and the type wheel is in the present instance swung back to the previously selected position. Subsequent impression of the same or a different character is accompanied by the

automatic inking of the same in the same manner prior to each impression.

The present invention provides in combination with the above features a simple and effective means for feeding the work between successive impressions operated by the impressing movement of the platen. Rotatably mounted at its ends in a bracket 44 on the base is a spindle 45 carrying a pair of feed rolls 46 projecting slightly through openings in the printing bed for engagement with the underside of the work which is held in contact with the feed rolls by a presser roller 47 rotatably carried on a spring actuated clip 48 pivotally mounted on the upper portion 11 of the frame for manual operation in the usual manner to release the work. The forward feed roll 46 carries a ratchet wheel 49 with forwardly projecting teeth or studs 50. Engaging with the latter is a pawl 51 in the form of an angular leaf spring, one end of which is secured to a bracket 52 fixed to the forward underside of the platen lever. The bracket carries also a stop 53 for preventing overthrow of the feed rolls. It is apparent from this construction that when the platen is raised to make an impression, the free end of the pawl is advanced idly to engage one of the teeth of the ratchet wheel and as the platen descends the pawl is lowered, thereby moving the ratchet wheel and the feed rolls through a predetermined distance for effecting the desired feeding movement of the work. At the end of each movement of the feed rolls and ratchet wheel the tooth of the latter engaged by the pawl is brought against a rearwardly projecting finger 54 on stop 53 to prevent overthrow. While the pawl is raised for the next operation, however, the stop 53 is raised with it and its finger 54 clears the ratchet wheel tooth so as not to interfere with the movement of the same. As the feeding movement terminates, finger 54 drops back to position across the path of the succeeding tooth to limit its movement.

The operations of the various parts of the apparatus have been described in detail in connection with the construction of the same and may be summarized as follows: The work having been located in the desired position on the printing bed to receive the first character of the impression or legend and being held by the presser roller 47, knob 28 is rotated to bring the dollar sign or any other desired initial symbol opposite the index 32. The handle 14 is then depressed and the type wheel is swung by the means described to effect inking contact of the selected type form with the inking roll 33 and to position the selected type form so inked in printing position above the platen. Continued depression of the

handle then raises the platen through the printing bed so that it presses the work from below against the selected type form above. Upon release of the handle the 5 parts are restored to position by spring 25, the type wheel being returned to the previously selected position ready for a second impression of the same or a different symbol. In this way a protective legend representing 10 any desired monetary value may be completed on the work. Each operation of handle 14 as described also accomplishes feeding coaction of ratchet wheel 49 and pawl 51 to rotate the feed rolls 46 to advance 15 the work step by step to receive successive impressions. The invention provides an exceedingly simple, reliable and effective mechanism characterized among other advantages by automatic inking of each 20 selected type form prior to each impression of the same whether employed once or a number of times in succession. The invention thus automatically insures the ample inking of the type forms at each 25 impression and hence the operation of the machine at maximum efficiency with the maximum degree of protection afforded by its use. Furthermore, the efficient impression of the work in this manner and the feeding 30 of the same between impressions are accomplished by mechanism of a simple compact and reliable character having obvious advantages from the point of view of manufacture and maintenance.

35 I claim as my invention:

I. In a printing apparatus, the combination of a platen, a rotary type wheel having a plurality of type forms thereon adapted to be brought by the rotation of said wheel 40 selectively to printing position opposite the platen, an inking device in the path of rotation of said type forms spaced from said printing position, operating means for effecting a relative impressing movement of said type wheel and platen, a member arranged for movement upon actuation of said operating means, and cam slot and follower means connecting said member and type wheel for oscillating the latter after 45 type selection to carry a selected type form from contact with said inking device to said printing position.

2. In a printing apparatus, the combination of a platen, a rotary type wheel having a plurality of type forms thereon adapted to be brought selectively to printing position opposite the platen, an inking device in the path of rotation of said type forms spaced from said printing position, operating means 55 comprising toggle links for effecting a relative impressing movement of said type wheel and platen, an arm on one of said links and cam slot and follower means connecting said arm and type wheel for oscillating the latter to carry a selected type form from

contact with said inking device to said printing position.

3. In a printing apparatus, the combination of a platen, a rotary type wheel having a plurality of type forms thereon adapted to be brought by the rotation of said wheel selectively to printing position opposite the platen, an inking device in the path of rotation of said type forms spaced from said printing position, operating means for effecting a relative impressing movement of said type wheel and platen, a plurality of cam slots in said type wheel, a member arranged for movement upon actuation of said operating means, and a follower on said arm 70 cooperating with said slots to oscillate said type wheel after type selection and carry a selected type form from contact with said inking device to said printing position.

4. In a printing apparatus, the combination of a platen, a rotary type wheel having a plurality of type forms thereon adapted to be brought selectively to printing position opposite the platen, an inking device in the path of rotation of said type forms 75 spaced from said printing position, operating means comprising toggle links for effecting a relative impressing movement of said type wheel and platen, a plurality of cam slots in one end of said type wheel, one to correspond with each of said type forms, and an arm on one of said links provided with a follower cooperating with said cam slots to oscillate said type wheel and carry a selected type form from contact with said inking device to said printing position and back to said inking device.

5. In a printing apparatus, the combination of a pivoted platen lever provided with a platen, a rotary type wheel having a plurality of type forms thereon adapted to be brought selectively to printing position opposite the platen, work feeding means, an inking device in the path of rotation of said type forms spaced from said printing position, an operating handle, toggle links connecting said handle and platen lever to effect an impressing movement of said platen, an actuating connection between said lever and feeding means, a plurality of cam slots 105 in said type wheel corresponding, respectively, to said type forms, and an arm actuated by said handle and provided with a follower cooperating with said cam slots to oscillate said type wheel and carry a selected type form from contact with said inking device to said printing position and back to said inking device.

6. In a printing apparatus, the combination of a pivoted platen lever provided with a platen, a rotary type wheel having a plurality of type forms thereon adapted to be brought selectively to printing position opposite the platen, an inking device in the path of rotation of said type forms spaced

from said printing position, operating means comprising toggle links for effecting impressing movement of said lever and platen, work feeding means comprising a ratchet wheel, a pawl on said lever for rotating said ratchet wheel, a plurality of cam slots in said type wheel, and an arm on one of

10 said links provided with a follower cooperating with said cam slots to oscillate said type wheel and carry a selected type form from contact with said inking device to said printing position and back to said inking device.

EDWARD S. SAVAGE.
